George H. Love,

INVENTOR:

ATTORNEY

UNITED STATES PATENT OFFICE.

GEORGE H. LOVE, OF PUEBLO, COLORADO.

TOOTH-BRUSH.

1,212,373.

Specification of Letters Patent. Patented Jan. 16, 1917.

Application filed January 29, 1916. Serial No. 75,150.

To all whom it may concern:

Be it known that I, GEORGE H. LOVE, a citizen of the United States, residing at Pueblo, in the county of Pueblo and State 5 of Colorado, have invented certain new and useful Improvements in Tooth-Brushes, of which the following is a specification.

This invention relates to an improved tooth brush and the principal object of the 10 invention is to provide improved means for rotatably mounting a tooth brush and to further provide improved means for rotating the brush so that the brush may be caused to rapidly rotate first in one direction, 15 and then in the opposite direction, the actuating lever for the shaft of the brush being carried by the handle of the brush and moved through the medium of the thumb.

Another object of the invention is to so 20 construct the brush that with a small amount of effort the brush can be caused to rotate very rapidly and thus the teeth thoroughly cleansed.

Another object of the invention is to so 25 construct the brush that it will comprise a comparatively few number of parts strongly connected to provide a durable, but at the same time light brush, easy to handle.

This invention is illustrated in the accompanying drawings wherein:—

Figure 1 is a view showing the brush in top plan; Fig. 2 is a view showing the brush in side elevation; Fig. 3 is a transverse sectional view taken along the line 3—3 of 35 Fig. 1.

The handle 10 of this brush is provided with a cut out forming a passage way 11 and is further provided with a bridge or guiding bracket 12 extending across the passage way 11 to guide the movement of the rack bar 13 carried by the actuating lever 14 and braced by means of the rod or bracing arm 15. This actuating lever is pivotally connected with the handle 10 by means of the thumb screw 16 and is yieldably held in the normal position by means of the spring 17 so that when pressure is released, it will be returned to the normal position, a finger 18 being provided to prevent the spring 17

from moving the rack bar 13 entirely out of the passage way 11. An eye 19 is provided for the thumb to fit into so that this lever can be easily moved by means of the thumb with the fingers passing through the eyes 20. 55

The brush housing 21 is provided with a collar or neck 22 which fits upon the end of the handle 10 and is secured in place by means of set screws 23. The shaft 24 of the brush 25 passes through the brush housing 21 and the end of the handle 10 and has each end formed into a pivot pin 26, which pivot pin fits into bearings 27 and 28 formed in the outer end of the brush housing 21 and in the end of the handle 10. A gear pinion 29 is rigidly mounted upon the brush shaft within the passage way 11 and is engaged by the teeth of the rack bar 13 so that as the rack bar is moved with the lever the brush shaft will be rotated according to the 70 direction in which the rack bar moves. It will thus be seen that when the brush is held with the fingers passing through eyes 20 and the thumb passing through eye 19, the actuating lever 14 can be moved toward the 75 handle and the brush will be rotated in one direction. Upon releasing the pressure upon the lever the spring 17 will return the lever to the normal position shown in Fig. 1 and the brush will be rotated in the opposite 80 direction. When it is desired to clean the brush, or replace the same with a new one, the brush housing can be removed from the handle after releasing set screw 23 and the shaft easily removed from the handle in 85 case it is desired to replace the brush, or if it is only desired to thoroughly clean the same, the brush can be cleaned and the brush housing then put back in place. I have therefore provided a tooth brush which 90 will be very easy to use and which will be so constructed that it can be easily cleaned and thus kept sanitary.

What is claimed is:

A brush comprising a handle provided 95 with a transversely extending cut out forming a passage way, a brush housing releasably connected with said handle, a brush positioned in said housing and provided with a shaft having one end rotatably sup- 100

ported by said housing and having the opposite end portion extended through said passage way and rotatably supported by said handle, a gear carried by said brush shaft, and an actuating lever carried by said handle and provided with a rack bar extending through the passage way and having its teeth meshing with the teeth of said gear.

In testimony whereof I affix my signature in presence of two witnesses.

GEORGE H. LOVE.
